Emery, Booth, Janney & Varney

UNITED STATES PATENT OFFICE.

DAVID W. BROOKS, OF NEW YORK, N. Y., ASSIGNOR TO CONCRETE STEEL COMPANY, OF NEW YORK, N. Y., A CORPORATION OF DELAWARE.

CONCRETE-INSERT.

1,267,178.

Specification of Letters Patent. Patented May 21, 1918.

Application filed July 31, 1917. Serial No. 182,809.

To all whom it may concern:

Be it known that I, DAVID W. BROOKS, a citizen of the United States, and a resident of the city of New York, county of New York, State of New York, have invented an Improvement in Concrete-Inserts, of which the following is a specification.

This invention aims to provide improved wall and ceiling devices, such for example as are employed in concrete construction work.

In the accompanying drawings, an illustrative embodiment of the invention is shown, wherein,

15 Figure 1 is a vertical longitudinal section of the apparatus taken on line 1—1 of Fig. 5, with attaching member and locking plate shown in full lines.

20 Figs. 2, 3 and 4 respectively are sectional views upon the same line 1—1 as Fig. 1, but showing various positions of the attaching member and locking plate.

Fig. 5 a plan view of Fig. 3,

25 Fig. 6 a perspective view of the locking plate and a portion of an attaching member, and

Fig. 7 a perspective view of the preferred locking plate.

Referring to Fig. 1, which shows one of the illustrative embodiments of this invention, I have provided a hanger or socket unit 10 adapted to be embedded in a wall, ceiling or other body commonly constructed of concrete, or it may be employed in other types of building structure. This hanger or socket is provided at its uninclosed side with flanges 11 preferably inturned, this uninclosed side constituting one form of base, which is not covered with concrete, but is positioned so that it is flush or substantially flush with the surface of the surrounding material. The hanger 10 is provided with external integral extensions or ears 12 preferably curved or otherwise formed to provide an anchorage adapted to be embedded in concrete for holding purposes. The hanger is also provided with centering or positioning lugs 13 having notches 14 adapted to receive nails or other securing or positioning members.

It will be observed that the inturned flanges 11 referred to, extend for a part only of the length of the socket walls so that there is provided between such flanges a

55 narrow opening which is enlarged beyond

said flanges. This forms what may be called a keyhole opening or entrance to the socket.

A portion of an attaching member as shown for illustrative purposes, takes the form of a bolt shank 15 with a head 16. 60 This attaching member co-operates with the hanger and may be of any design which will best co-operate with any particular design of a hanger in order that the parts be properly held together.

65 To guard against accidental disengagement of the attaching member from its socket I have provided a locking member 17 herein shown as a comparatively thin plate, slotted to straddle the shank 15 of the attaching member and ends 18 are upturned to engage the head 16 of said attaching member. The plate is preferably of sinuous form or is deflected somewhat to facilitate its entrance into the socket beneath the head of the attaching member as shown in Figs. 1 and 4, such deflection also acting to shorten the overall length of said plate.

70 When assembling the attaching device, the locking plate 17 is placed astride the shank 15 and the ends 18 engage the head 16. These members are inclined and thrust into the socket through the large part of the key-hole opening. By reason of the deformation of the plate 17 the attaching member passes into the socket. If the underside of the locking plate 17 rests upon the ends 19 of the flanges 11 there will be ample room for the head 16 of the hanger member to 75 pass into the recess without contact with the upper part of the wall 20. The attaching member may be moved horizontally in order to properly align it with other like attaching members, such, for instance as 80 may be employed in hanging shaftings. When the attaching member is fastened in normal position, the locking plate is flattened and its length increased. Should the attaching member become loose and move to 85 the right as shown in Fig. 4, the head 16 would engage with the upper part of the wall 20 and the bottom side of the locking plate 17 would engage with the ends 19 of the flanges 11 while the end of the plate 90 would engage with the wall 20 just above the edge of the key-hole opening, thereby effecting a three-point contact which would prevent the discharge of the attaching member from the socket.

It is to be understood that all matter herein set forth or shown in the accompanying drawings is to be interpreted as illustrative and not in a limiting means.

5 I claim as my invention:

1. In a device of the character described, in combination, a hanger having a recess therein and supporting flanges in said recess, an attaching member adapted to engage said flanges, and a coöperating deformable locking plate assembled therewith for movement into said recess, said plate being deformable within said recess to lock said attaching member therein.
- 15 2. In a device of the character described, the combination of a hanger having a recess therein and supporting flanges in said recess, a headed attachment member adapted to engage said flanges and a waved locking plate movable into said recess with said attachment member and adapted to be forced against said flanges and thereby elongated to form a locking means by coöperation with a wall of said hanger.
- 25 3. A concrete insert comprising a hollow body portion provided with internal supporting flanges forming an elongated slot with an enlarged opening at one end for the insertion of an attachment member, deformable locking means resting upon said flanges, and a headed attachment member adapted when drawn down to deform said locking means and be retained in operative position thereby.
- 35 4. A concrete insert comprising a hollow body portion provided with internal sup-

porting flanges forming an elongated slot with an enlarged opening at one end, a headed attachment member for insertion through said end opening, and a locking device assembled with said attachment member for insertion therewith and adapted by cooperation with the end wall of said opening to retain the attachment member in operative position upon said flanges.

45 5. The combination with an insert for concrete construction comprising a hollow body portion with internal supporting flanges and provided with an entrance passage for a headed attachment member, of a locking member adapted to be inserted with a headed attachment member and interposed between said member and said flanges and there to be deformed to retain said attachment member in operative position upon the flanges.

6. The combination with an insert for concrete construction comprising a hollow body portion with internal supporting flanges and provided with an entrance passage for a headed attachment member, of a slotted locking plate having means to engage the head of said attachment member and adapted to be inserted therewith and interposed between the said member and said flanges to retain said attachment member upon the flanges by coöperation with an end wall of the insert.

In testimony whereof, I have signed my name to this specification this 30th day of July, 1917.

DAVID W. BROOKS.
